BOOK BINDING

Paul W. Bidwell, Holyoke, Mass., assignor to
White & Wyckoff Mfg. Company, Holyoke,
Mass., a corporation of Massachusetts

Application June 17, 1935, Serial No. 26,894

13 Claims.

(Cl. 11—1)

This invention relates to improvements in book binding and is directed more particularly to improvements in apparatus and methods for cutting off and crimping or turning in the ends of 5 bindings for books of the type shown and described in U. S. Letters Patent to Eden, No. 1,986,757, issued January 1, 1935.

The principal objects of the invention are directed to the provision of improvements in apparatus and methods for cutting off and crimping or turning in the ends of bindings which are formed from wire or the like to have rings which pass through the perforations of leaves of the books and are spaced apart by connecters.

15 Another object of the invention is the provision of an apparatus for cutting off and crimping or turning in the ends of the bindings.

Various other novel objects and advantages of the invention will be hereinafter more fully referred to in connection with the accompanying 20 description of the preferred form of the invention, reference being had to the drawing wherein:

Fig. 1 is a front elevational view of an apparatus embodying the novel features of the invention and adapted to carry out the novel 25 method thereof;

Fig. 2 is a sectional plan view on the line 2—2 of Fig. 1;

Fig. 3 is an enlarged elevational sectional view 30 on the line 3—3 of Fig. 1;

Fig. 4 is a front elevational view of the apparatus shown in Fig. 3;

Fig. 5 is a side elevational view of the crimping 35 device shown in Fig. 3 taken at an opposite side thereof;

Fig. 6 is a plan view of the endmost portion of a book with the binding therein to explain how it is acted upon by the crimper of the invention;

Fig. 7 is an edge view of a book and binding 40 showing the binding before it is cut off and crimped; and

Fig. 8 is a view similar to Fig. 7 showing the binding after it has been cut off and crimped in accordance with the invention.

45 Referring now to the drawing more in detail, the invention will be fully described.

A base 2 is provided in which is oscillatable and reciprocable a shaft 4 which carries the crimping mechanism. A rack 6 is movable in a plane 50 transverse to the axis of shaft 4 and may be actuated by any suitable means. In the form of the invention shown, the rack 6 is operated by an armature 8 of a solenoid 10 supported by uprights 12 which are carried by the base 2.

55 The shaft 4 has a gear 14 associated therewith

which is in engagement with the rack 6 whereby it is oscillated and a cam 16 on the end of shaft 4 formed with a cam groove 18. A cam follower 20 on a block 22 associated with the base brings about reciprocatory movements of the shaft as it is oscillated.

The outer end of the shaft 4 as shown in Figs. 3, 4, 5 and 6 carries a projection or horn 40 which in part provides the crimping and cutting off mechanism. The part 40 in the position shown 10 is ready to receive the binding and it then rotates or oscillates counterclockwise from the position shown in Fig. 4 through an angle of approximately 180°.

The shaft 4 is slotted longitudinally and it is 15 cut away on a side thereof as shown at 30 in Fig. 6. A latch member 32 is disposed in the slot of the shaft 4 and has a forward detent portion 34, a lug portion 36 is disposed in the recess 30 and is arranged for rocking movements on a pin 38. 20 The forward part 40 of the shaft 4 constituting the crimper is slotted transversely on its end as indicated by 42 to receive the binding. A cutting edge 44 is provided on the outer side of the part 40 adjacent slot 42 as shown in Figs. 4 and 5 25 which co-operates with a cutting edge 66 of a cutter 64 above the part 40.

The lower forward side of the detent 34 of the latch 32 is curved as shown in Fig. 3. The latch 32 is mounted for swinging movements and it is 30 possible therefore in the position of the shaft shown in Fig. 3 to insert the binding in the slot 42 by pressing it against the detent. This causes the latch 32 to be elevated to expose the slot. When the binding is in the recess 42 the latch 35 moves downwardly so that the binding is enclosed in said groove by the said latch detent. A spring 46 in a socket 48 acts on the rear end of the latch 32 and tends to hold it in the position 40 shown in Fig. 3.

As the shaft 4 rotates counterclockwise from the position in Fig. 4 through an angle of approximately 180°, a part 33 of the latch engages and rides onto a cam 50 disposed in a slot 52 in the lower side of the base which causes the inner end of the latch to be depressed, the outer end carrying the detent 34 to be elevated, to uncover slot 42 and permit the binding to be withdrawn from the slot 42. The rack 6 by being reciprocated in opposite directions causes the shaft 4 to oscillate in opposite directions, counterclockwise for a cutting and crimping operation and then clockwise.

An abutment 60 is disposed below the part 40 55

and this may be associated with the plate 62 secured to the under side of the base 2.

As disclosed in the patent to Eden, No. 1,986,757, a binding B usually of wire may consist of a plurality of rings or loops 70 which extend through openings 72 of the leaves of a book L. The ends of the rings 70 are connected by longitudinal bars or spacers 74. In the binding of the book, the binding is usually longer than the book so as to extend beyond the edges thereof as shown in Figs. 6 and 7. It is to cut off the excess binding and crimp or turn in the end portion of the binding that the apparatus and method of this invention relates and it is accomplished in the following manner.

That bar 74' of the binding B which is outside that ring or loop 70' thereof which passes through the endmost perforation 72' of the book is inserted in the notch or groove 42 of the part 40. This is accomplished by pressing the bar 74' against detent 34. The book is held in a substantially horizontal plane, while the rack 6 is actuated to rotate the shaft 4 and crimper mechanism counterclockwise. As the shaft 4 is thus rotated the cutting edges 66 and 44 of the shear and of the part 40 co-operate to sever the binding near the outer end of bar 74' or at a point away from the last ring or loop 70'. As the said shaft 4 rotates the said bar of the binding is turned counterclockwise so that it is turned inwardly alongside of bar 74 extending from ring 70'.

As has been explained, during this counterclockwise oscillation of the shaft 4 it is moved rearwardly or axially to some extent by means of cam groove 18 and projection, (see Fig. 2). This is so that the bar 74' will not be brought over onto the next adjacent bar 74 connected to ring 70' but instead will be positioned at a side thereof as shown in Fig. 8.

When the shaft 4 has been oscillated through its angle of movement to cut off the binding and crimp or turn the bar 74' inwardly, the portion 33 of the latch 32 will bring up against the cam 50 whereby the outer end or detents 34 of the latch 32 is elevated to uncover notch 42 whereupon the binding is released so the book may be pulled forwardly.

It will be noted that by means of the method and apparatus that the binding is cut and crimped simultaneously in a simple and efficient manner and is accomplished by the novel means described.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. An apparatus for binding a book wherein the binding includes a continuous piece of wire having rings passing through perforations of a book which are connected at opposite ends by bars comprising in combination, a support, a rotatable member therein provided with a slot for receiving that bar of the binding which extends outwardly from the ring in the last perforation of the book which is rotatable to turn said bar inwardly into parallelism with the axis of the binding, and means for cutting off said bar at a distance from said ring as said member rotates.

2. An apparatus for binding a book wherein the binding includes a continuous piece of wire

having rings passing through perforations of a book which are connected at opposite ends by bars comprising in combination, a support, a rotatable member therein provided with a slot for receiving an endmost bar of the binding extending outwardly from an endmost ring of the binding and which is rotatable to turn said bar inwardly of the binding into parallelism with the axes thereof, a latch pivoted to said rotatable member having a part overlying said slot which is engageable and movable by the said bar to permit insertion of the bar in said slot whereby said bar is enclosed in said slot, and means to operate said latch and remove said part away from said slot to permit withdrawal of the said bar therefrom, the said means being arranged for operation after the member has been rotated for turning the bar inwardly.

3. An apparatus for binding a book wherein the binding includes a continuous piece of wire having rings passing through perforations of a book which are connected at opposite ends by bars comprising in combination, a support, a rotatable member therein provided with a slot for receiving an endmost bar of the binding extending outwardly from an endmost ring of the binding and which is rotatable to turn said bar inwardly of the binding, a latch pivoted to said member having a part overlying said slot which is engageable and movable by the said bar to permit insertion of the bar in said slot whereby said bar is enclosed in said slot, and means to operate said latch and remove said part away from said slot to permit withdrawal of the said bar therefrom, the said means being arranged for operation after the member has been rotated for turning the bar inwardly, and means operable during rotation of said member to sever said bar at a point away from said endmost ring of the binding.

4. An apparatus for binding a book wherein the binding includes a continuous piece of wire having rings passing through perforations of a book which are connected at opposite ends by bars comprising in combination, a support, a rotatable member therein provided with a slot for receiving an endmost bar of the binding extending outwardly from an endmost ring of the binding and which is rotatable to turn said bar inwardly of the binding, a latch pivoted to said member having a part overlying said slot which is engageable and movable by the said bar to permit insertion of the bar in said slot whereby said bar is enclosed in said slot, and means to operate said latch and remove said part away from said slot to permit withdrawal of the said bar, the said means being arranged for operation after the member has been rotated for turning the bar inwardly, and means to reciprocate said member during its rotation to move said inwardly turned bar out of alignment with that bar of the binding next adjacent thereto.

5. An apparatus for crimping a spiral binding comprising in combination, a support, a rotatable member therein having a slot, a latch pivoted to said member having a part to close the entrance to said slot, means tending to hold the same in slot-closing position, means to rotate said member, means engageable by said latch as the member rotates to move said part from slot-closing position disposed for operation when the member has rotated through a certain angle, and means for severing a binding carried by said slot operable by rotation of said member.

6. An apparatus for crimping a spiral binding

- comprising in combination, a support, a rotatable member therein having a slot, a latch pivoted to said member having a part to close the entrance to said slot, means tending to hold the 5 same in slot-closing position, means to rotate said member, means engageable by said latch to move said part from slot-closing position disposed for operation when the member has rotated through a certain angle, means for severing a binding 10 carried by said slot operable by rotation of said member, the said means including a stationary cutting edge and a cutting edge co-operating therewith associated with said rotatable member.
7. An apparatus for cutting off the end portion 15 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, means to move said member axially during rotation thereof, a latch pivoted to said rotatable member for movements between slot closing and slot 20 opening positions having a part to overlie and close said slot, means to urge the said latch to slot closing position, means to move said latch from slot closing position, and means for severing a binding during rotation of said crimping member.
8. An apparatus for cutting off the end portion 25 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said rotatable member for movements between slot closing and slot opening positions having a part to overlie and close said slot, means to urge said latch to slot closing position including a spring associated with the crimping member bearing on said latch, 30 means to move said latch from slot closing position, and means for severing a binding during rotation of said crimping member.
9. An apparatus for cutting off the end portion 35 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said crimping member having a forward end part adjacent said slot to open and close the same as the latch swings on said member, means to urge the said latch to slot closing position, means to move said latch from slot closing position, and means for severing a binding during rotation of said crimping member.
10. An apparatus for cutting off the end portion 40 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said rotatable member for movements between slot closing and slot opening positions having a part to overlie and close said slot, means to urge the said latch to slot closing position, means to move said latch from slot closing position including a member associated with said support engageable by said latch and adapted to move the same during rotation of the crimping member.
11. An apparatus for cutting off the end portion 45 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said rotatable member for movements between slot closing and slot opening positions having a part to overlie and close said slot, means to urge said latch to slot closing position including a spring associated with the crimping member bearing on said latch, 50 means to move said latch from slot closing position, and means for severing a binding during rotation of said crimping member.
12. An apparatus for cutting off the end portion 55 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said rotatable member for movements between slot closing and slot opening positions having a part to overlie and close said slot, means to urge the said latch to slot closing position, means to move said latch from slot closing position including a member associated with said support engageable by said latch and adapted to move the same during rotation of the crimping member.
13. An apparatus for cutting off the end portion 60 of a book binding having a plurality of connected loops or rings in the perforations of the leaves of the book and turning the endmost portion of the binding inwardly comprising, a support, a crimping member rotatable in the support having an end portion extending from said support provided with an axially disposed slot for receiving said binding, means to rotate said member, a latch pivoted to said rotatable member for movements between slot closing and slot opening positions having a part to overlie and close said slot, means to urge the said latch to slot closing position, means to move said latch from slot closing position, and means for severing a binding during rotation of said crimping member including co-operating cutters carried by said support and crimping member adapted to act on a binding extending from the slot of 65 the crimping member.
